The ornamental design for a table, as shown and described.

DESCRIPTION

FIG. 1 is a top perspective view of a table, showing my new design.

FIG. 2 is a bottom perspective view thereof.

FIG. 3 is a right side elevational view thereof.

FIG. 4 is a left side elevational view thereof.

FIG. 5 is a front elevational view thereof.

FIG. 6 is a rear elevational view thereof.

FIG. 7 is a top plan view thereof; and,

FIG. 8 is a bottom plan view thereof.

The broken line showing of elements on the table illustrate portions of the article and forms no part of the claimed design.
